UNITED STATES PATENT OFFICE.

AUGUSTUS T. GUILBERT, OF PASADENA, CALIFORNIA.

DESIGN FOR A STATUETTE LAMP STAND.

Application filed November 26, 1921. Serial No. 518,105. Term of patent 3½ years.

To all whom it may concern:

Be it known that I, AUGUSTUS T. GUILBERT, a subject of the King of Great Britain, residing at Pasadena, in the county of Los Angeles, State of California, have invented a new, original, and ornamental Design for Statuette Lamp Stands, of which the following is a specification, reference being had to the accompanying drawing, forming a part thereof.

The figure is a view in perspective of my statuette lamp stand.

I claim:

The ornamental design for a statuette lamp stand as shown.

A. T. GUILBERT.
